UNITED STATES PATENT OFFICE

HORACE L. RIDGERS, OF GRANUM, ALBERTA, CANADA

HACK SAW

Application filed April 24, 1929, Serial No. 357,818, and in Canada April 19, 1929.

The invention relates to improvements in hack saws and an object of the invention is to provide a hack saw with a handle which can be swung to either side when desired, this permitting one to manipulate the saw in locations where the customary straight handle could not be used without the fingers gripping the handle rubbing the work or other obstruction.

10 A further object is to construct an adjustable handle which can be locked in the adjusted positions and which is effectively braced when in the normal position.

A further object is to provide a saw with a 15 handle having the above features and which in no way interferes with the customary adjustment provided to accommodate blades of varying length.

20 A further object is to provide the adjustable handle feature in a simple, durable and inexpensive manner and so that the adjustment can be easily and quickly made.

25 With the above more important objects in view, the invention consists essentially in the arrangement and construction of parts hereinafter more particularly described, reference being had to the accompanying drawing, in which:—

Fig. 1 is a side view of a saw, parts being 30 broken away to expose construction.

Fig. 2 is a plan view of the handle in the normal or straight position.

Fig. 3 is a plan view of the handle turned to the side.

35 Fig. 4 is an enlarged detailed vertical sectional view at A'—A Figure 2.

Fig. 5 is a perspective view of parts carried by the handle.

Fig. 6 is a perspective view of the pivot 40 arm having the T-shaped slot therein.

Fig. 7 is a vertical sectional view at 7—7' Figure 1.

45 In the drawing like characters of reference indicate corresponding parts in the several figures.

The back 1 of the saw is of suitable length and is of an inverted U-shape in vertical cross section and it receives slidably an adjustable blade supporting arm 2 which is notched at 50 the under side as indicated at 3, the notches

being adapted to receive the pin 4 carried by the channel shaped back. The forward end of the arm 2 is downturned and is supplied with a sleeve 5 receiving slidably a bolt 6 which has the front end thereof screw threaded to receive the wing nut 7 and the rear end provided with a pin 8 which supports the forward end of the saw blade 9, the blade being provided with the customary forward opening to receive the pin.

55 All the above parts are commonly used on hack saws at the present time, the arm 2 being adjusted by swinging the forward end thereof upwardly to release the pin from one slot 3, then pulling the arm ahead or forcing it back and re-entering the pin in a further slot and finally swinging the arm down to its original position, the adjustment accommodating the length of the blade which it is desired to use. The blade is also tightened 60 up in the usual manner by manipulating the thumb nut 7.

65 To the rear end of the saw back, I secure 70 permanently as by riveting as indicated at 10 a downwardly extending standard 11 which has the lower end thereof provided with a square sleeve 12 slidably receiving a square bar 13 which is provided forwardly with a pin 14 adapted to enter the rear hole of the blade and has the rear end thereof fitted 75 with stop means 15 preventing the bar withdrawing forwardly out of the sleeve. It will be observed that the back of the handle extends rearwardly beyond the upper end of the standard and forms a socket 16 to receive 80 parts later disclosed, the said socket having the sides thereof provided with horizontal slots 17.

85 To the rear end of the saw back, I secure 90 pivotally a lever arm 18 which has the rear end thereof offset to clear the back and provided with a substantially T-shaped slot 19. This slot receives slidably a pivot pin 20 carried by an arm 21 which extends forwardly from a bar 22 permanently carried by the 95 upper end of the handle 23. The forward end of the bar 22 is fitted with a forwardly projecting contracted extension 24 adapted to slidably enter the socket 16 formed at the rear end of the saw back and the extension 100

is provided at the sides with guides 25 adapted to slidably enter the slots 17, the arrangement being such that when the extension is in the socket, the handle is in its normal position 5 directly behind the saw. The slot 19 is designed to permit the extension to be entered into and withdrawn from the sleeve.

It will be observed that the pin 20 is somewhat back from the forward end of the arm 10 21 and that the forward end of the latter arm carries an upstanding stationary screw 26 which passes slidably through an elongated slot 27 formed in the rear end of a swinging lever 28, the forward end of which is pivotally fastened at 29 to the forward end of the saw back. The screw is supplied with a jam nut 30 located above the rear end of the lever 28 and the arrangement is such that when the nut is tightened up, the rear end of the 20 lever 28 is releasably fastened to the underlying end of the arm 21.

To the sleeve 12, I permanently secure a short rearwardly extending arm 31 to which I pivotally connect at 32 a swinging arm 33 25 which has the rear end thereof provided with an elongated slot 34. A stationary screw 35 extends downwardly from the under side of the handle which it will be observed carries also a plate 36 having a roughened under face 30 and the screw passes slidably through the slot and has the lower end thereof fitted with a washer 37 and a winged nut 38.

From the above it will be obvious that when the nuts 30 and 38 are loosened, one can 35 pull the handle rearwardly to withdraw the extension 24 from the socket 16, the slots 27 and 34 accommodating this movement. After the extension has been withdrawn from the socket, one can shift the handle to either 40 side as desired in order to give ample room for the fingers gripping the handle when one is working in difficult places where the fingers otherwise might be rubbing the work or adjoining structure. When the handle is 45 swung to the side, the lower arm 33 swings on the pivot pin 32 and the upper arm swings freely, the pins 20 and 26 sliding in the slots 19 and 27 and the levers 18 and 28 swinging to accommodate the movement.

50 When the handle has been placed in the adjusted position, one tightens up the nuts 30 and 38 which locks the handle in the adjusted position. One can then use the saw in the usual manner and without rubbing the fingers on the work or other structure. When the handle is returned to its normal position, it is only necessary to force the extension 24 ahead until it firmly seats in the socket 16 and then tighten up the nuts.

60 The back 1 and the standard 11 of the saw form a rigid frame which I term the saw frame.

What I claim as my invention is:—

1. In a hack saw, the combination, with 65 the saw frame, of a handle detachably con-

nected to the rear end of the frame by a sliding joint disengageable in the rear pulling of the handle, a lever arm pivotally attached to the top of the frame and provided at its free end with a lengthwise extending slot, an upper arm extending from the upper part of the handle and connected to the lever arm by a pin slidably operating in the slot, a swinging lower arm pivotally connected to the lower rear part of the frame and having the free end thereof adjustably fastened to the lower end of the handle, a swinging lever pivotally connected to the upper part of the saw frame and having the rear end thereof adjustably fastened to the forward end of the upper swinging arm, and means for locking the handle and frame in adjusted position.

2. In a hack saw, in combination, a horizontally disposed back bar, a standard extending downwardly from the bar, a handle detachably connected to the rear end of the bar by a sliding joint disengageable in the rear pulling of the handle, a lever arm pivotally secured to the rear end of the back bar and having the free end thereof extending rearwardly and provided with a longitudinally extending slot, an arm extending forwardly from the upper part of the handle and overlying the rear end of the lever arm and connected slidably thereto by a pin in the arm operating in the slot, a swinging lever having the forward end thereof pivotally connected to the forward end of the back bar and the rear end thereof longitudinally slotted and overlying the arm carried by the handle, a pin carried by the latter arm and passing through the latter slot, a jam nut screw threaded on the pin, a lower swinging arm pivotally attached to the lower end of the standard having the free end thereof longitudinally slotted and underlying the lower end of the handle, a screw carried by the handle extending through the slot and the jam nut mounted on the screw.

Signed this 24th day of December, 1928.
